WALL TILE

Anthony J. Izewski, Franklin Park, Ill.

Application October 21, 1955, Serial No. 38,508

Term of patent 14 years

(Cl. D18—2)

Fig. 1 is a front elevational view of a wall tile showing my new design;

Fig. 2 is a rear elevational view thereof;

Fig. 3 is a top plan view thereof; and

Fig. 4 is a vertical sectional view thereof taken substantially along the line 4—4 of Fig. 1.

The dominant features of my design reside in the portions shown in full lines.

I claim:

The ornamental design for wall tile, as shown and described.
